(57) **CLAIM**

The ornamental design for a remote entry keypad and enclosure, therefor as shown and described.

DESCRIPTION

FIG. 1 is a top, front, and left side perspective view of a remote entry keypad and enclosure showing a first embodiment of my new design;

FIG. 2 is a top plan view thereof;

FIG. 3 is a bottom plan view thereof;

FIG. 4 is a front elevational view thereof;

FIG. 5 is a left side elevational view thereof;

FIG. 6 is a right side elevational view thereof;

FIG. 7 is a top, front, and left side perspective view thereof, with the hinged door moved to an open position, and the broken-line disclosure of a keypad being for illustrative purposes only and forming no part of the claimed design;

FIG. 8 is a top, front, and left side perspective view showing a second embodiment thereof, with the hinged door moved to an open position; and,

FIG. 9 is a front elevational view of a second embodiment thereof, with the hinged door moved to an open position. The rear elevational view forms no part of the present invention.
